UNITED STATES PATENT OFFICE.

EDWARD B. CANTEY, OF COLUMBIA, SOUTH CAROLINA.

INSTRUMENT FOR CUTTING CORES FROM SOLID SUBSTANCES.

1,162,901.

Specification of Letters Patent.

Patented Dec. 7, 1915.

Application filed October 8, 1915. Serial No. 54,915.

To all whom it may concern:

Be it known that I, EDWARD B. CANTEY, a citizen of the United States, residing at Columbia, in the county of Richland and State of South Carolina, have invented certain new and useful Improvements in Instruments for Cutting Cores from Solid Substances; and I do hereby declare the following to be a full, clear, and exact description of the same, reference being had to the accompanying drawings, forming part of this specification, and to the figures and letters of reference marked thereon.

This invention relates generally to an improved instrument for cutting cores from solid substances.

For convenience in description, and in order to facilitate a clear understanding of the nature and objects of the invention, the following illustration is given of one use to which the novel instrument can be applied: In taking samples from rosin barrels, when they are offered for sale in the market, it has been heretofore necessary to take the head off the barrel and remove a considerable portion of the rosin in order to get a satisfactory sample of the contents of the barrel. This results in a considerable waste of rosin, and also in the danger of not effecting a sale, in that the rosin near the head of the barrel, which is frequently cloudy and impure, is exposed to the prospective purchaser, even though the rosin farther down in the barrel is perfectly clear and readily salable. By the use of the improved instrument of the present invention, it will not be found necessary to unhead the barrel of rosin at all, in taking samples, but the side of the barrel can be penetrated or tapped by an ordinary auger, the instrument inserted into the hole, and a core of rosin cut out and withdrawn by the instrument. As a consequence, the amount of rosin wasted in taking the sample is very small, and, in addition, it is necessary to remove only the better grade of rosin in the barrel, thereby increasing the probabilities of a sale.

A preferred form of instrument for effecting this result is illustrated in the accompanying drawings, in which:

Figure 1 is a perspective of an instrument constructed in accordance with the present improvements. Fig. 2 is a longitudinal section taken midway through the

same. Fig. 3 is a transverse section taken in a plane indicated by the line $y-y$ of Fig. 2, looking in the direction of the arrow 3. Fig. 4 is a transverse section taken in a plane indicated by the line $4-4$ of Fig. 2. Fig. 5 is a transverse section on line $y-y$ of Fig. 2 looking in the direction of the arrow 5.

Like characters of reference in the several figures indicate the same parts.

As shown in the drawings, the instrument includes a core cutting blade which consists of a hollow member or tube A formed of inner and outer walls, a , a' , and having one end a^2 shaped to provide a lateral cutting edge, whereby the tube may be forced into a mass of rosin or other solid substance. Surrounding the tube at its opposite end is a jacket B having an inner flange B', said jacket being preferably constructed of heat insulating material in order that the tube may be readily grasped by the hand, when cutting the core from the mass of rosin.

Heat is applied to the walls of the tube A by means of electric wires C extending in the space between the inner and outer walls of the tube and terminating in heating coils or resistances C' located adjacent the lateral cutting edge at the inner end of the tube. The electric wires C may be connected to any suitable source of current supply, by means of sockets or terminals C² extending through the handle B. To prevent the walls of the tube C from becoming electrified, said walls are lined with a suitable non-conducting substance, as indicated at c in Fig. 2 of the drawings.

Supported by brackets d, d' attached to the inner wall A of the tube is a shaft or rod D, which rod extends from an opening or slot D' located adjacent the flange B' of the handle B, to approximately the inner end a^2 of the tube. Said rod lies against the inner wall a of the tube and is provided at its end adjacent the lateral cutting edge with a knife blade D² lying in a plane approximately transverse to the axis of the rod. At its other end, the rod is provided with an angular extension D³, which projects through slot D' and forms a handle, whereby the rod D may be oscillated through a limited arc, and the knife D' shifted from a position against the inner wall of the tube, as shown in full lines in Fig. 3, to a position wherein the tip of the

blade lies approximately in the central axis of the tube, as shown in dotted lines in Fig. 3.

5 Mounted on a rod e is a plunger E having a side opening E' , whereby the plunger may slide along the rod D . Rod e is supported in a recess plug e^2 which closes the end of the tube adjacent handle B and extends outwardly through said plug to a push button 10 E^3 . Surrounding the rod e and seating in the recess of the plug E^2 is a spring e' which exerts pressure on the inner face of push button E^3 in a direction to force the plunger out of the tube, the outward movement of the plunger being limited by the plug E^2 .

In operation, a hole is first bored in the side of a barrel of rosin, for example, by an ordinary auger, and the walls of the tube 20 are heated by connecting the sockets C^2 with any suitable source of current supply. Heating the walls melts the rosin along the line of cut, and facilitates forcing the tube into the mass of rosin in the barrel, which 25 is done by simply grasping the handle B of the tube and pushing it in the hole bored by the auger. When the instrument has been pushed in the material the required distance to cut the side walls of a 30 core of the desired length, the handle D^3 is shifted to extend the knife blade D' into the cutting position previously described. Then, by giving the tube a turn the knife blade D' cuts off the inner end of the core. When 35 the instrument is withdrawn from the barrel the core of rosin is within the tube A and may be readily removed therefrom by shifting the knife blade D' back to its normal position against the inner wall of the 40 tube and pushing in the plunger E to force out the core of rosin. The heated walls of the tube soften or melt the outer portion of the core of rosin and assist the plunger in forcing the core out of the tube. By the 45 operation of the improved instrument, the sampling of barrels of rosin and other substances may be effected with considerable rapidity and with a minimum waste of material. The instrument is particularly 50 advantageous for sampling barrels of rosin, in that it is not necessary to unhead the barrel and expose to the prospective pur- 55 chaser the cloudy and impure rosin which is generally found in the upper portion of the barrel near the head. Only the clear rosin is exposed to the prospective pur- chaser,—a commercial factor of considerable importance.

What is claimed is:

60 1. An instrument for cutting cores from solid substances, including, in combination, a core cutting blade adapted to be forced into the substance, a second blade lying normally against the inner wall of the core cutting blade, and means for extending said

second blade into position with its tip lying approximately in the central axis of the core cutting blade, whereby a rotary movement of the second blade is effective to cut off the inner end of the core. 70

2. An instrument for cutting cores from solid substances, including, in combination, a core cutting blade adapted to be forced into the substance, means for heating said blade to assist in forcing it in, and another 75 blade located adjacent the operative end of the core cutting blade and operable to cut off the inner end of the core.

3. An instrument for cutting cores from solid substances, including, in combination, 80 a core cutting blade adapted to be forced into the substance, a second blade lying normally against the inner wall of the core cutting blade, means for extending said second blade into position with its tip lying approximately in the central axis of the core cutting blade, whereby a rotary movement of the second blade is effective to cut off the inner end of the core, and means for heating the core cutting blade to assist in forcing 85 it in. 90

4. An instrument for cutting cores from solid substances, including, in combination, a hollow member adapted to be forced into the substance and to cut the side walls of the core, electric heating wires extending parallel with the side walls of the hollow member, and a blade located adjacent the operative end of the hollow member and operable to cut off the inner end of the core 100 and permit its removal from the main body of the substance.

5. An instrument for cutting cores from solid substances, including, in combination, 105 a hollow member adapted to be forced into the substance and to cut the side walls of the core, electric heating wires extending parallel with the side walls of the hollow member, a blade lying normally against the inner walls of the core cutting blade, and means for extending said blade into position with its tip lying approximately in the central axis of the hollow member, whereby a rotary movement of the hollow member is effective to also rotate the blade and cut off 110 the inner end of the core. 115

6. An instrument for cutting cores from solid substances, including, in combination, 120 a hollow member adapted to be forced into the substance and to cut the side walls of the core, electrical heating wires extending parallel with the side walls of the hollow member, a blade located adjacent the operative end of the hollow member and operable to cut off the inner end of the core and permit its removal from the main body of the substance, and a plunger for ejecting the core from the hollow member. 125

7. An instrument for cutting cores from solid substances, including, in combination, 130

- a hollow member adapted to be forced into the substance and to cut the side walls of the core, electrical heating wires extending parallel with the side walls of the hollow member, a blade located adjacent the operative end of the hollow member and operable to cut off the inner end of the core and permit its removal from the main body of the substance, a plunger for ejecting the core from the hollow member, a spring exerting pressure to force the plunger normally out of the hollow member, and means for limiting the outward movement of said plunger. 8. An instrument for cutting cores from solid substances, including, in combination, a tube having a lateral cutting edge at one end thereof whereby it is adapted to be forced into the substance and cut the side walls of the core, a blade lying normally against the inner wall of the tube, and means for extending said blade into position with its tip lying approximately in the central axis of the tube, whereby a rotary movement of the blade is effective to cut off the inner end of the core. 9. An instrument for cutting cores from solid substances, including, in combination, a tube having inner and outer spaced walls and a lateral cutting edge at one end thereof, whereby the tube is adapted to be forced into the substance and cut the side walls of the core, electric heating wires in the space between the inner and outer walls of the tube, and a blade located adjacent the lateral cutting edge of the tube and operable to cut off the inner end of the core. 10. An instrument for cutting cores from solid substances, including, in combination, a tube having inner and outer spaced walls and a lateral cutting edge at one end thereof, whereby the tube is adapted to be forced into the substance and cut the side walls of the core, electric heating wires in the space between the inner and outer walls of the tube, and a plunger for ejecting the core from the hollow member, a spring exerting pressure to force the plunger normally out of the hollow member, and means for limiting the outward movement of said plunger. 11. An instrument for cutting cores from solid substances, including, in combination, a tube having inner and outer spaced walls and a lateral cutting edge at one end thereof whereby the tube is adapted to be forced into the substance and cut the side walls of the core, electric heating wires in the space between the inner and outer walls of the tube, a blade lying normally against the inner wall of the tube, and means for extending said blade into position with its tip lying approximately in the central axis of the tube, whereby a rotary movement of the blade is effective to cut off the inner end of the core. 12. An instrument for cutting cores from solid substances, including, in combination, a tube having inner and outer spaced walls and a lateral cutting edge at one end thereof, whereby the tube is adapted to be forced into the substance and cut the side walls of the core, electric heating wires in the space between the inner and outer walls of the tube, a blade lying normally against the inner wall of the tube, means for extending said blade into position with its tip lying approximately in the central axis of the tube, whereby a rotary movement of the blade is effective to cut off the inner end of the core and permit its withdrawal from the main body of the substance, a plunger for ejecting the core from the tube, a spring exerting pressure to force the plunger normally out of the tube, and means for limiting the outward movement of the plunger.
